LIPSTICK HOLDER.

Gunnard P. Peterson, Naugatuck, Conn., assignor
to The Risdon Manufacturing Company, Naug-
atuck, Conn., a corporation of Connecticut

Application October 15, 1938, Serial No. 235,162

5 Claims. (Cl. 206—56)

The invention relates to lipstick holders and the like in which a contained cosmetic or other pencil is projected and retracted by a rotary or screwing action. Its object is to produce a simple structure providing smooth and easy movement for the cup or elevator in which the pencil is held, and capable of production at low manufacturing cost. To this end, the invention consists, among other things, in forming the elevator cup and the actuator sleeve respectively with portions embossed out of the material thereof and mutually engaging so that their relative rotation reciprocates the elevator cup, as explained below.

15 In the accompanying drawing

Fig. 1 is a longitudinal section of the present preferred form of the invention applied to a lipstick holder, and taken by way of example;

Fig. 2 is a similar section at right angles to Fig. 1 but showing the inner sleeve in elevation, and

20 Fig. 3 is a perspective of the elevator cup.

The elevator cup, marked 1, slides in the inner sleeve 2 which is provided with a straight slot marked 3. The elevator is by preference provided with an inwardly-bossed circular bead 4, serving as a seat or stop shoulder for the cosmetic pencil designated 5 and is formed to have an easy sliding fit in its sleeve. It is also formed with two outwardly bossed nibs 6, one directly above, and the other directly below the groove produced by the bead 4. These nibs project into and through the straight slot 3. The elevator thus turns with the sleeve when the latter is rotated. The nibs 6 are preferably made by slitting the side wall of the cup to form a strap and bulging the strap outwardly, with the proper shape. See Fig. 3. Although the nibs may be otherwise formed, this method of embossing produces straight edges by which they engage the edges of the slot 3 and makes for smooth travel.

The inner sleeve 2 is shouldered at 7 and again at 8, and its larger end portion constitutes an operating head or thumb piece designated 9, which may be knurled if desired and by means of which the inner sleeve 2 and elevator can be turned with respect to the surrounding or actuator sleeve marked 10.

This outer sleeve is formed with an inwardly projecting helical track 11 preferably in the form of an embossed bead and of such cross-sectional contour as to make a proper operating engagement with the notch formed between the two elevator nibs 6 which, as already stated, project through the slot 3. Relative rotation between

the inner and outer sleeves will thus result in longitudinal movement of the elevator. Such movement may be limited in the downward direction by the impingement of the lower nib upon the lower end of the slot 3, or of an elevator stop finger 12 upon the end wall 13 of sleeve 2, as preferred. In the upward direction it is limited by the engagement of the upper nib with the upper end of the nib slot 3.

The outer sleeve 10 is confined on the inner sleeve 2 at one end by the shoulder 8 and at the other by a circular outwardly bossed bead 14 on the inner sleeve 2 located near its upper end. As will be seen in Fig. 2 this bead 14 forms the upper bearing for the outer sleeve 10 and overlies the top end of the helical track or bead 11 thereon, thereby retaining the sleeve on the shoulder 8. The sleeve 10 may also be supported intermediate its end by the bearing which its helical boss has upon the surface of the inner sleeve.

For assembling the parts the inner sleeve 2 is cut or slit directly above the upper end of the nib slot 3. This slit is indicated at 15 in Fig. 2, and extends through the circular bearing bead 14. It is a reduced continuation of the slot 3 and permits the walls of the inner sleeve to be spread apart far enough to pass the nibs 6 of the elevator and admit them into the nib slot 3. The same slit also permits the walls of the inner sleeve to be thereafter squeezed together so as to allow the helical track on the outer sleeve 10 to be passed over the circular bearing bead 14 and seated on the shoulder 8. On the return of the inner sleeve to its normal diameter, indicated in the drawing, all the parts are confined in their final working relation. The helical track is snapped into the nib notch and when the cap or cover 16 has been applied, the article is complete and is composed of but four pieces, each of which can be rapidly made in automatic machinery. The cap 16 as here shown seats on the same shoulder 8 as forms the bearing for the actuator sleeve, as a matter of preference, and is provided with a moderate friction on the latter to guard against its dropping off, but this friction is less than that which would be required to turn the actuator sleeve by turning the cap, so that if the cap should be turned in the process of removal or replacement or otherwise, the position of the elevator will not be affected. While as here shown the outer surface of the outer sleeve is exposed when the cap is removed, it will be understood that it can be enameled or otherwise embellished or encased, if desired, for the sake

of appearance. It will be understood also that, as above stated, the embodiment of the invention above described, is exemplary only and not in limitation of the principles of construction and assembly defined by the claims.

5 I claim:

1. In a lipstick holder, the combination of an inner slotted sleeve, an outer sleeve rotatably confined thereon, an inwardly projecting helical bead embossed on the outer sleeve, an elevator in the inner sleeve formed with two outwardly embossed nibs one above the other having rounded extremities and projecting through the slotted sleeve, said helical bead being formed to ride 10 on the exterior surface of the inner sleeve and said embossed nibs to embrace and ride on said embossed helical bead.

15 2. The construction of the preceding claim in which said embossed nibs on the elevator have straight vertical boundaries to be guided in the slot of said inner sleeve.

20 3. In a lipstick holder, the combination of an inner slotted sleeve, an elevator slidable therein and provided with two nibs formed of cut portions of the elevator wall outwardly bulged to 25

project through the slot in said sleeve, one above the other, and an outer sleeve rotatably confined on said inner sleeve and provided with an inwardly projecting helical track engaged between said nibs.

5 4. In a lipstick holder, the combination of an inner slotted sleeve, an elevator slidable therein and provided with an inwardly embossed circular groove and two outwardly embossed nibs on each side of said groove projecting through the slot in said sleeve, and an outer sleeve rotatably confined on said inner sleeve and provided with a helical track engaging the notch between said nibs.

10 5. In a lipstick holder, a casing having a helical track, an inner slotted sleeve and an elevator in such sleeve having means to engage said track and slot including a strap cut from the wall of the elevator, connected to such wall by both its ends and bulged outwardly at its middle to form 15 a projection extending through said slot into engagement with said track and presenting the cut edges of the strap to the edges of the slot in said sleeve.
